CLAIM

The ornamental design for a pants, as shown and described.

DESCRIPTION

FIG. 1 is a front perspective view of pants showing my new design;

FIG. 2 is an additional front perspective view thereof;

FIG. 3 is a front view thereof;

FIG. 4 is a rear view thereof;

FIG. 5 is a side view thereof;

FIG. 6 is an opposite side view thereof;

FIG. 7 is an enlarged view of region 7 in FIG. 2;

FIG. 8 is a front view of the pants of FIGS. 1-7 shown in a flattened state; and,

FIG. 9 is a rear view thereof.

The broken lines depicting the remainder of the pants show features that form no part of the claimed design.
